(57) **CLAIM**

The ornamental design for a multi-use light housing shroud, as shown.

DESCRIPTION

FIG. 1 is a perspective view of the multi-use light housing shroud of the present invention;

FIG. 2 is a reverse angle perspective view of the multi-use light housing shroud of the present invention;

FIG. 3 is a front view of the multi-use light housing shroud of the present invention;

FIG. 4 is a rear view of the multi-use light housing shroud of the present invention;

FIG. 5 is a top view of the multi-use light housing shroud of the present invention; and

FIG. 6 is a bottom view of the multi-use light housing shroud of the present invention; and,

FIG. 7 is left side view of the multi-use light housing shroud of the present invention (the right side view is a mirror image).

The broken lines in the drawings illustrate features of the multi-use light housing shroud that form no part of the claimed design.
